R. J. NEAL

HEATING DEVICE FOR AUTOMOBILES

Filed March 31, 1924

WITNESS:

UNITED STATES PATENT OFFICE.

RALPH J. NEAL, OF DURHAM, NORTH CAROLINA.

HEATING DEVICE FOR AUTOMOBILES.

Application filed March 31, 1924. Serial No. 703,229.

My present invention has reference to a heating device for automobiles or similar motor propelled vehicles.

An object is to produce a hot water heating device in which water is heated in a water jacket or drum arranged in an auxiliary muffler connected with the exhaust pipe of the engine, and directed therefrom through the radiators, a valve controlling the passage in the exhaust pipe between the auxiliary muffler and the main muffler whereby the heated exhaust gases may be directed through either of the mufflers, so that the heater may be used only when necessary.

With the above broadly stated objects in view, and others which will appear as the nature of the invention is better understood, reference is to be had to the drawings which accompany and which form part of this application.

In the drawings:—

Figure 1 is a sectional plan view of an automobile illustrating the arrangement of the radiators therein.

Figure 2 is a horizontal sectional view through the bypass showing the valve in one position by full lines and in its second position by dotted lines.

Figure 3 is a substantially central longitudinal sectional view through the muffler in which the boiler is arranged, the latter being also in section.

Figure 4 is a transverse sectional view through the device disclosed in Figure 3.

The numeral 1 designates an automobile or similar motor-driven vehicle. The engine for the automobile is indicated by the numeral 2 and the exhaust pipe therefrom by the numeral 3. The exhaust pipe communicates with the ordinary muffler 4. In the present instance there is a branch pipe 5 between the exhaust pipe and the muffler 4. A similar but oppositely directed branch pipe is also attached to the outlet end of the exhaust pipe, and the branch pipe 6 communicates with an auxiliary muffler 7. As the muffler constructions may be of the ordinary character, a detailed description thereof will not be attempted.

In the auxiliary muffler 7 there is a boiler 8, and heated gases passing through the exhaust pipe 3, directed through the muffler 7, will heat water in the boiler 8. The boiler 8 comprises a tubular member of a length less than that of the muffler 7. The water jacket is closed at both of its ends, but has its

ends disposed in a line with the pipe 6 from the exhaust manifold formed with a central opening surrounded by a tubular member in the nature of a flue 8' that is directed into the boiler casing. The inner end of the flue is closed, as at 8'', and this end terminates a suitable distance away from the closed outer end of the boiler. The boiler is centrally supported in the muffler 7 by brackets 7' that may be formed on the sides of the boiler or otherwise secured thereto and that have their outer ends widened for the reception of bolts or analogous means whereby the said brackets are fixed on the inner sides of the muffler 7. By this arrangement the heat from the manifold passing through the branch 6 of the bypass will be directed into the flue 8', and after circulating therethrough will be directed through the mouth 70 of the flue through the muffler 7, such heat, of course, contacting with the outer surface of the boiler for effectively heating the water therein. Of course, a certain amount of the heat from the exhaust finds an 80 indirect passage through the muffler 7, but, the construction is such that the water in the boiler will be heated in a quick and efficient manner. At the juncture of the branch pipes 5 and 6 with the exhaust pipe 3 there 85 is a valve 9. This valve has its stem offset, and connected thereto there is a rod 10 that leads to the front of the body of the automobile. The rod may be connected to a pivotally supported lever which is conveniently 90 arranged with respect to the driver of the machine, and whereby the valve can be turned to cause the exhaust gases from the engine to be directed through the main muffler 4 or through the auxiliary muffler 7. 95

Connected to the boiler 8 there is an upwardly directed pipe 11. This pipe has an offset branch 12 provided at its outer end with an upwardly directed funnel extension 13, a closure 14 being provided for the funnel. The funnel affords a means whereby water is delivered into the boiler 8. The pipe 11 has a branch 15 extending inwardly and longitudinally of the body of the automobile, but preferably beneath the floor 100 thereof. The pipe 15 is provided with upwardly directed vertical branches 16 and 17 respectively, and these branches are in turn connected to radiators 18 and 19 respectively. The outlet ends of the radiators have 110 connected therewith short pipes 20 and 21 respectively forming branches of the main

pipe 22 that is directed into the hollow center of the boiler.

It is, of course, to be understood that the boiler is spaced from the sides of the auxiliary muffler 7, and from the foregoing description, when taken in connection with the drawings, it will be seen that by turning the valve 9, the exhaust hot gases from the engine may be directed through either of the 10 mufflers 4 or 7. When directed through the latter, the water in the boiler will be heated, and such heated water will be delivered to the radiators. The radiators are conveniently arranged with respect to the passengers at the front and back of the automobile. 15 When the heater is not in use, it is merely necessary to turn the valve to direct the heated gases through the muffler 4.

Having described the invention, I claim:—

A heating device for automobiles, including a casing connected with the exhaust pipe from the engine of an automobile, a boiler in the casing, said boiler comprising a cylindrical member closed at one of its ends and having the other end thereof, adjacent to the 25 heat inlet for the casing provided with a central opening, disposed in a line with said inlet, a tubular member surrounding the opening, secured to the said end of the boiler, extending therein and having its inner 30 end closed but disposed away from the outer closed end of the boiler, means between the sides of the boiler and the inner sides of the casing for holding the boiler centrally in the casing, an inlet water pipe for the boiler 35 and an outlet water pipe for the boiler.

In testimony whereof I affix my signature.
RALPH J. NEAL.
